UNITED STATES PATENT OFFICE.

WILLIAM M. WHITNEY, OF WINCHENDON, MASSACHUSETTS.

ROTARY CUTTER.

1,308,313.

Specification of Letters Patent. Patented July 1, 1919.

Application filed March 23, 1917. Serial No. 156,970.

To all whom it may concern:

Be it known that I, WILLIAM M. WHITNEY, a citizen of the United States, residing at Winchendon, county of Worcester, and 5 State of Massachusetts, have invented an Improvement in Rotary Cutters, of which the following description, in connection with the accompanying drawings, is a specification, like characters on the drawings representing like parts.

The invention to be hereinafter described relates to tools and more particularly, to rotary cutters for milling machines and the like.

15 The blades of such cutters experience hard usage, and require frequent sharpening to maintain them in proper working condition. This sharpening reduces the length of the blades and consequently they must be adjusted to compensate for their reduction in 20 length and to retain the original effective working diameter of the cutter. Also, the blades must be adjusted so as to project equally from the body of the cutter in order 25 that each shall perform its share of the work.

The present invention provides simple, strong, and effective means for adjusting the blades relatively to the body of the cutter, and securing the same in their different 30 positions of adjustment.

The character of the invention may be best understood by reference to the following description of one good form of the invention shown in the accompanying drawing, wherein:

Figure 1 is a perspective view of a cutter embodying the invention;

Fig. 2 is a perspective unassembled view 40 of a blade and devices for securing the same to the body of the cutter; and

Fig. 3 on an enlarged scale is a sectional view showing a portion of the body of the cutter, a blade, and securing and adjusting 45 devices therefor.

Referring to the drawing: The device there shown as embodying the invention is a rotary cutter comprising a body 1 of polygonal shape having a hub 3 provided with 50 a slot 5 for receiving the usual key for securing the cutter to the spindle of a milling or other machine.

The body serves as a carrier for a series 55 of tools, in the present instance of the invention, in the form of blades 7 having their

outer ends beveled and sharpened to present forward cutting edges 9.

These tools are suitably mounted on the body and to this end, in the present instance of the invention, the body is provided with 60 peripheral recesses 11 projecting in a general radial direction and with the planes of said recesses oblique to the plane of the body of the cutter. The blades may be of a thickness corresponding to the recesses and have a 65 close sliding fit therein, but preferably project laterally somewhat beyond the sides of said body.

Next will be described means for adjusting and securing the blades in said recesses. 70 To accomplish this, each blade may be provided with a screw 15 or equivalent member. In the present instance of the invention this screw is interposed between a wall of a blade and a wall of the recess in which the blade 75 is mounted, but is threaded to merely one of said walls, the construction being such that on rotation of the screw the blade will be adjusted outward relatively to said body. Preferably, the walls engaged by the screw 80 are mating grooves 17 and 19, one being in the back of the blade and the other being in the rear wall of and communicating with the recess. The groove of the tool is threaded, whereas the groove of the recess 85 is smooth. Consequently, in assembling the parts, it is merely necessary to present the screw laterally to the groove of the blade with the threads thereof intermeshing. Then the blade and screw may be slid as a 90 unit into the recess.

Preferably, the threads are square or blunt to facilitate their slide along and pressure against the recess groove without injury to either the teeth or said groove. 95

When the screw and blade are mounted in the recess, the screw should be confined against inward movement. This may be accomplished by engagement of the inner end of the screw with a suitable abutment 100 which may conveniently be the bottom 21 of the recess.

Thus, the screw not only constitutes a simple and effective means for adjusting the blade, but by its positive engagement with the blade and with the base of the recess, positively prevents inward movement of the blade after it is adjusted to the desired position.

The screw may have a slot 23 in its outer 110

end for receiving a screw driver in adjusting the same and preferably the top of the screw does not project out beyond the periphery of the body, but is substantially flush therewith and consequently is in out of the way of the active end of the blade.

The construction is such that when the screw is rotated it reacts on the bottom of the recess and forces the blade outward.

10 Obviously, by this means, all of the blades may be set equally with any desired nicety of adjustment as required.

Since the blade may be readily adjusted outward, it is not necessary to employ a long

15 blade which will extend a substantial distance beyond the periphery of the body to allow for reduction in the length thereof from sharpening. On the contrary, a shorter blade may be used having its active 20 cutting edge projecting merely a short distance beyond the periphery of the body of the cutter. Consequently, substantially the entire length of the blade is backed and supported by the rear wall of the recess. This 25 enables the use of blades made of very hard but brittle steel.

To prevent outward movement of the blade after adjustment thereof, a pin 25, preferably tapering, may be set in a groove 30 27 extending transversely to the plane of the body and communicating with the recess for securing the blade. This pin will engage the front face of the blade and press the latter and the screw toward the back wall of 35 the recess.

The screw preferably is located between the blade and the wall of the recess opposite the forward cutting edge of the blade. As a result, in use, the pressure on said edge 40 forces the blade back against the screw and tight engagement of their threads is assured.

Since the screw is confined in the mating grooves of the blade and recess, it positively prevents the blade from sliding in its recess

transversely to the plane of the body of the cutter. 45

Thus, the single screw may serve to adjust the blade outward, to limit its movement inward, and to prevent its movement laterally of the cutter.

50 The parts of the cutter are few in number, simple and strong in construction, and easily assembled and adjusted.

It will be understood that the invention is not limited to the specific embodiment 55 shown, but that extensive deviation may be made therefrom without departing from the spirit and scope of the appended claim.

What is claimed is:—

A rotary cutter comprising in construction, a body having blade receiving recesses, the front and rear walls of which extend uninterruptedly from the outer to the inner limits of the recesses, blades mounted in said recesses and provided with uninterrupted front and threaded rear faces, a screw of uniform dimension from end to end engaging the rear threaded face of each blade, said screw and its associated blade being adapted to be inserted in a recess of the body in assembled relation, transversely extending wedge receiving openings formed in the body transversely of and communicating with the blade receiving openings through the front walls thereof, and flat faced 75 wedges adapted to be inserted in said transversely extending wedge shaped openings and acting to force the screws into close contact with the threaded rear face of the blades and against the smooth unthreaded rear walls of the recesses to lock the blades and permit ready removal or insertion of the blades and screws while in assembled relation.

80 In testimony whereof, I have signed my name to this specification.

WILLIAM M. WHITNEY.
